(57) **CLAIM**

The ornamental design of a fabric filter dewatering tube for collecting sediment, as shown and described.

DESCRIPTION

FIG. 1 is a perspective view of a fabric filter dewatering tube for collecting sediment showing my new design, with a middle portion broken away to disclose indefinite length;

FIG. 2 is an end view thereof; and,

FIG. 3 is an opposite end view thereof.

The cross-line pattern, which is partially shown for ease of illustration, represents a conventional fabric and is understood to repeat uniformly throughout the indicated area.
